UNITED STATES PATENT OFFICE.

JOSEPH J. MEYER, OF CHICAGO, ILLINOIS.

DESIGN FOR AN INVERTED HYDROCARBON-VAPOR LAMP.

No. 40,015.

Specification for Design.

Patented May 25, 1909.

Application filed March 31, 1909. Serial No. 487,099. Term of patent 3½ years.

To all whom it may concern:

Be it known that I, JOSEPH JOHN MEYER, a citizen of the United States, and resident of Chicago, in the county of Cook and State of Illinois, have invented a new, original, and ornamental Design for an Inverted Hydrocarbon-Vapor Lamp, set forth in the annexed specification, reference being had to the accompanying sheet of drawings, forming part thereof.

The figure in the drawing is an elevation showing my new and original design.

I claim:

The ornamental design for an inverted hydrocarbon vapor lamp, as shown.

J. J. MEYER.
